UNITED STATES PATENT OFFICE.

RICHARD PACKER AND ISAAC E. COCHRAN, JR., OF CHESTER,
PENNSYLVANIA.

ELECTRIC-LIGHT BURGLAR-ALARM INDICATOR.

SPECIFICATION forming part of Letters Patent No. 393,657, dated November 27, 1888.

Application filed July 6, 1887. Serial No. 243,591. (No model.)

To all whom it may concern:

Be it known that we, RICHARD PACKER and ISAAC ENGLE COCHRAN, Jr., of Chester, county of Delaware, State of Pennsylvania, have invented a new and useful Improvement in Electric Light Burglar-Alarm Indicators, of which the following is a full, clear, and exact description, reference being had to the accompanying drawings, making part of this specification.

Our invention relates to improvements in electric burglar-alarms; and it consists of the peculiar combination and arrangement of devices, as will be hereinafter fully described, and particularly pointed out in the claims.

The object of our invention is to automatically illuminate an incandescent lamp simultaneously with the sounding of the bell in the alarm circuit, the bell or alarm mechanism and incandescent lamp being each included in separate distinct circuits, which are operated continuously and independently of each other (after the alarm-circuit has been completed or closed by the door or window connection) by separate batteries until switched off by suitable devices included in the respective circuits.

A further object of our invention is to provide a burglar alarm system with a series of electric incandescent lamps, each having a word, letter, figure, or other character to distinguish them from one another and to denote the different apartments or points of the residence.

A further object of our invention is to provide a secondary lamp circuit, which is connected at its terminals, primary lamp and alarm circuit, and a switch, whereby the current in the primary lamp-circuit can be caused to traverse the secondary lamp-circuit, which runs through one or more apartments of the house and includes one or more electric lamps of the incandescent pattern, so that after the lamp in the primary lamp-circuit has been operated and the alarm mechanism sounded the lamp in the apartment from which the alarm is "sprung" can be readily illuminated.

In the accompanying drawings, Figure 1 is a view illustrating a single burglar-alarm system embodying our invention. Fig. 2 is a view showing a series of circuits which run through different apartments and having the incandescent lamps in the primary circuit

thereof bearing distinguishing characters. Fig. 3 is a detail horizontal sectional view on the line *x x* of Fig. 1.

We will now proceed to describe our invention in connection with the drawings, in which like letters of reference denote corresponding parts in all the figures.

A and *B* designate primary independent circuits, each of which has a battery, *C C'*, respectively, for operating the primary circuits independently of each other. The primary circuit *A* includes therein a bell and its operating mechanism *D*, and the circuit *B* includes an electric lamp, *E*, of the incandescent type, these circuits *A* and *B* being hereinafter termed the "primary alarm-circuit" and the "primary lamp-circuit," for the purpose of distinguishing them from one another and of referring to the same. The alarm mechanism and incandescent lamp of the two primary circuits may be of any preferred pattern, and we therefore will not particularly describe herein the construction of the parts thereof, and the batteries, which may be of the storage or other pattern, of the primary circuits operate the respective devices included in the said circuits independently of each other.

F' is the connection, which is applied to either the door, window, or other place where unwarranted interference is likely to occur, and this connection is included in the primary alarm-circuit, so that when the door, &c., is opened, or forced the alarm-circuit is completed to cause a current from the battery *C* to traverse the said circuit. In lieu of the door or window connection of the pattern shown herein, an electric door-mat of any well-known or preferred pattern may be included in the alarm-circuit.

G is the relay, having the usual contact base or plate, *f*, provided with the vertical insulated pin *f'*, the helices *g*, and the lever-arm *g'*, arranged over the helices to be attracted thereby and serve as an armature, one end of this armature, which is normally elevated, being adapted to come in contact with the insulated vertical pin *f'* of the relay, to thereby complete the circuit through the relay-contacts when the helices are energized, in the manner which we will presently describe.

One of the wires of the alarm-circuit leading from the door or window connection *E* is connected with the helices of the relay, and it

runs from the latter to the alarm mechanism, and thence back to the battery C, thereby completing the alarm-circuit.

One of the wires, b, of the primary lamp-circuit is connected to the vertical insulated pin of the relay, and the other wire, b', of the same circuit is connected to the contact-base of the relay, so that when the current of the alarm-circuit energizes the helices of the relay the armature is depressed to cause the free end of the armature to contact with the insulated pin, and thereby close the primary lamp-circuit, the current from the battery of which traverses the wire b', thence through the base of the relay and armature thereof, and through the wire b, connected to the insulated pin f', to the lamp E, and from the latter to the battery C', which thus completes the primary lamp-circuit.

20. Each of the primary circuits A, B has a cut-out switch, H or H', by means of which the currents in either circuit can be independently cut out to extinguish the lamp in the primary lamp-circuit, or stop the alarm in the alarm-circuit, these switches being entirely independent of one another, so that either circuit can be continued in use without hindrance from the other circuit. The switch H in the primary alarm-circuit is preferably connected 25 with the return battery-wire at some distance from the relay, while on the other hand the switch H' of the primary lamp-circuit is connected to the wire b at a point near where the wire is connected to the relay, for a purpose 30 which will presently appear.

I designates a secondary lamp-circuit, which runs to the apartment in which the connection or mat E' is located, said circuit having an incandescent lamp, I', included therein, which 40 is located at a suitable point in the apartment to illuminate the latter. One of the terminals of the secondary lamp-circuit I is arranged in close proximity to the switch H' of the primary lamp-circuit, so that the switch can be caused 45 to contact with said terminal to cause the current from the primary lamp-circuit to traverse the wires of the secondary lamp-circuit, and the other terminal of the circuit I is connected at a suitable point to the return battery- 50 wire of the primary lamp-circuit.

When the switch H' of the primary lamp-circuit is operated to close the same, the current from the battery traverses through the lamp E included in the said circuit; but when 55 the primary lamp-circuit is broken by opening the switch H' the current from the battery C' traverses the secondary lamp-circuit through the lamp therein to illuminate the apartment from which the alarm is sprung, 60 and is thence returned to the battery to complete the secondary circuit through the return-wire of the primary lamp-circuit. By these devices the attendant is notified of the unwarranted interference with the dwelling, 65 and he is enabled to illuminate the apartment from which the alarm is sprung with ease and entire safety.

In Fig. 2 we have shown a series of circuits having the lamps in the primary circuits provided with distinguishing figures, as j, characters, words, &c., to denote the apartment with which they are connected. The lamp and bell of the two primary circuits are located in a sleeping-apartment or other place to awaken a servant or watchman and notify him of the unwarranted interference with the building and the point where the disturbance is caused.

The operation of our invention is obvious from the foregoing description. Upon closing the circuit in the primary alarm-circuit 80 a current from the battery C traverses the helices in the relay to energize the same and continues to the alarm mechanism to operate the same. The armature of the relay is attracted by the helices to contact with the insulated pin f', and thus close the primary lamp-circuit. The switch H' in the latter circuit being closed, a current from the battery C' traverses the primary lamp-circuit, and thence to the battery by the return-wire. Should the attendant desire, the switch H' 90 may be operated to break the primary lamp-circuit and switch the current around the secondary lamp-circuit to illuminate the lamps therein, and thus light up the apartment where 95 the burglary is attempted.

We would state that while we deem the mechanism and devices herein shown and described as best adapted for carrying our invention into practice, still we do not desire to 100 confine ourselves to the exact construction and arrangement of devices, as we are aware that changes can be made therein without departing from the spirit of our invention.

Having thus fully described our invention, 105 which we claim as new, and desire to secure by Letters Patent, is—

1. In an electric burglar alarm, substantially as described, the combination, with two primary circuits, one having an alarm mechanism and the other an incandescent lamp, and batteries for energizing said circuits, of a secondary lamp-circuit including an incandescent lamp, and a switch for diverting the current from one of the primary circuits to 110 said secondary lamp-circuit, substantially as described.

2. In an electric burglar-alarm, the combination, with two primary circuits, each having a battery and one including an audible 115 alarm mechanism and the other an incandescent lamp, a relay, and a door or window connection included in one of the circuits and adapted to close the same, of a secondary lamp-circuit having an incandescent lamp included 120 therein, and a switch for diverting the current of the primary lamp-circuit to the secondary lamp-circuit, as and for the purpose described.

In testimony whereof we have hereunto set our hands this 15th day of June, A. D. 1887.

RICHARD PACKER.
